SHIPPING CASE OR CRATE AND SHOOK THEREFOR

George G. Wheat, Brooklyn, N. Y.

Application June 4, 1940, Serial No. 338,710

2 Claims. (Cl. 20—4)

1

This invention relates to panels to be assembled and united to form hollow structures, and while they may be used in the construction of different forms of structures they are particularly adapted for use as shooks in constructing shipping cases, boxes or crates.

It is an object of the invention to provide an improved box or case shook or panel consisting of a plurality of wood pieces, such as boards or planks, assembled in edgewise joined relation by tongues and grooves, and the provision of means to engage and extend transversely of the width of boards or planks to retain them in edgewise assembled relation under a compression force acting against the resiliency of the wood and adapted to distribute and take up uniformly throughout the entire panel or shook the force of lateral stresses transmitted thereto.

While the shook or panel is adapted for use in the construction of different structures, and is particularly adapted for use in the construction of shipping cases, boxes or crates wherein a shook or panel, or two or more of said shooks or panels assembled in edgewise relation, constitute the sides, top and bottom of the structure, and wherein means engaging and extending transversely of the width of the boards or planks serve to joint them in edgewise relation and take up in the shook or panel the stresses of forces transmitted laterally thereto, they also serve to secure and unite the shooks assembled in the case or crate while maintaining the shook boards under a compression force and effect an equalized or balanced distribution of strength throughout the case or crate and uniformly distribute and take up through all the parts of the case or crate any stress or stresses of a load therein exerted on a part or parts of the case or crate, and thus adapting the shooks or panels to the construction of a shipping case, box or crate which is not only simple in construction and low in cost but highly efficient in use.

Other objects and advantages of the invention will hereinafter appear.

In the drawings accompanying and forming a part of this application,

Figure 1 is a front elevation of my improved shook or panel and showing the same in edgewise assembled relation under the force of a compression pressure by tie rods.

Figure 2 is a view on an enlarged scale looking at the end of the shook or panel shown in Figure 5.

Figure 3 is an end elevation, on an enlarged scale, of a pair of the boards of a shook or panel

showing the manner of adhesively uniting the same and providing tunnels between the boards or adjacent shooks or panels for the passage of tie rods.

5 Figure 4 is a perspective view, on an enlarged scale and partly broken away, of a board or plank showing the manner of arranging mortises in the ends thereof and engaging tenons or splines therein to connect the boards of a shook or adjacent shooks and arrange the mortise with tunnels for the passage of tie rods.

Figure 5 is a perspective view of a shipping case constructed of shooks, shown in Figure 1.

15 Figure 6 is a perspective view on an enlarged scale and broken away, of a corner portion of the case shown in Figure 5, to show the manner of uniting the members of the case.

Figure 7 is a perspective view showing a modified construction of a shipping case constructed 20 from shooks shown in Figure 1.

Figure 8 is a sectional view on an enlarged scale taken substantially on the line 8—8 of Figure 7 to show the connecting of members to the shooks or panels to constitute skids of the shipping case.

25 Figure 9 is a view similar to Figure 8 showing a modified construction of members connected to the shooks or panels to constitute skids for a shipping case.

30 Figure 10 is a sectional view on an enlarged scale taken substantially on the line 10—10 of Figure 7 to show the manner of connecting a shook or shooks constituting the top of a shipping case to a shook or shooks constituting a side of the shipping case.

Figure 11 is a perspective view showing the shooks assembled in a further modified construction of shipping case.

35 Figure 12 is a sectional view in perspective on an enlarged scale, of a portion of the case shown in Figure 11, the section being taken substantially on the line 12—12 of said Figure 11 to show the manner of connecting shooks constituting the top and bottom of a shipping case to the shooks or panels constituting the sides thereof.

Figure 13 is a fragmentary view in perspective on an enlarged scale and partly broken away, of a corner portion of the casing shown in Figure 11 to show the manner of connecting shooks constituting the sides to the top of the shipping case; and

40 Figure 14 is a fragmentary view in perspective on an enlarged scale and partly shown in section, the section being taken through the case between 45 adjacent shooks, as on the line 14—14 of Figure

11, and showing a modified arrangement of connecting the shooks constituting the top and bottom of a shipping case to a shook constituting a side of the case and the connecting of members to said shook constituting a side of the case and constituting skids for the case.

The shook or panel as shown in Figure 1 is constructed of wood pieces, such as boards or planks 14 having parallel pairs of grooves 15 arranged in one longitudinal edge in the direction of the grain of the boards or planks and a pair of parallel tongues 16 extending along the opposite longitudinal edge in the direction of the grain. The boards or planks are joined in edge-wise relation by engaging the tongues of one board in the grooves of an adjacent board. To seal the joint between the tongues and grooves the grooves are made of greater depth than the distance or extent to which the tongues project from the board and the portion intermediate the tongues, as at 17, is in a plane inwardly from the portions 17' outwardly from the tongues whereby when the boards are joined the bottom of the grooves will be spaced from the tongues, as shown at 18, and the portion intermediate the tongues will be spaced from the opposed portion of the adjacent board, as at 18'. Prior to joining the boards an adhesive, such as glue, is doctored onto the surface between the tongues of the boards and it may also be applied to the edge portion between the grooves, the glue as the boards are joined and drawn together oozing from between the portion 17 of the boards along a side of the tongues and into the space between the bottom of the grooves and tongues, as shown by stippling in Figure 3 relative to the spaces 18, 18'.

To distribute and take up through the boards or planks of the shook any stresses of forces transmitted laterally to the shook or panel the opposite ends of the boards are mortised along the width thereof, the mortises being disposed midway the thickness of the wood pieces intermediate the tongues and grooves and being of a width substantially equal to the space between the bases of the tongues and grooves, as shown at 19, and extend into the boards, as indicated at 19', the side walls of the mortises being chamfered and decline to the bottom of the mortise, as at 19''. Tenons or splines 20, preferably wood pieces, of a width less than the depth of the mortises are engaged in the mortises and the space between the bottom of the mortise and tenons or splines constituting tunnels extending transversely of the width of the shook. The one edge of the tenons engaged in and opposed to the bottom of the mortise is recessed, as at 21, the side walls of the recesses declining from the sides of the tenons to the bottom of the recess, as at 21'. The boards in assembling and joining of the same by the tongues and grooves, as shown in Figure 2, are subjected edgewise of the force of a compression pressure against the resiliency of the wood of the boards by forcibly drawing the boards together by suitable means, such as tie rods 22 extended through the mortise tunnels and nuts threaded onto said rods and retained in said condition until they are to be used in the construction of a hollow structure, such as a shipping or packing case, box or crate. The shooks or panels, as shown in Figure 1, are adapted to be used singly or in multiple in the construction of a shipping case, box or crate of rectangular form, and when only one of the shooks is to be utilized for the sides, ends, top and bottom of the

case the nuts are removed from the tie rods and the shooks positioned so that certain of the shooks will overlie the ends of the tunnels and others of the shooks connected thereto by extending the ends of the tie rods through the portions of the shooks overlying the ends of the tunnels.

In Figure 5 there is shown a shipping case or box constructed in accordance with the present invention from shooks, as shown in Figure 1. As shown, each of the side members of the case includes a pair of shooks *a*, *a'*, each of the end members a pair of shooks *b*, *b'*, and the top and bottom members each include a pair of shooks *c*, *c'*. In assembling the members of the case the end and side members are first assembled by positioning the end members with the face adjacent the ends engaging or abutting the opposite longitudinal edges of the side members and with the longitudinal edges of the end members spaced from the ends of the side members, as shown at 23 in Figure 6, the end and side members being secured in said position by tie rods 22' engaged in the tunnels of the side members, the tie rods being of a length greater than the width of the two shooks *a*, *a'* and extended through openings in the end members, as at 24, and nuts threaded onto the ends of the tie rods drawing the end members to the side members of the case and placing the shooks of the side members and the boards thereof under a compression force. The shooks *c*, *c'* of the top and bottom members are then positioned between the end portions of the side members projecting beyond the side edges of the end members, as at 25, and the side edges of the side members engaging the top and bottom members, as at 26, and the top and bottom members secured in such position by tie rods similar to the tie rods 22' extended through the tunnels in the end, top and bottom members, the tie rods extended through the tunnels of the top and bottom members being extended through openings in the side members, and the tie rods extended through the tunnels in the end members extended through openings in the top and bottom members, and nuts threaded onto said tie rods also drawing the top and bottom members to the end members and holding the shooks of the end members under a compression force.

By the arrangement of mortising tenons into the ends of the shooks there is provided a deep cord or I beam effect with the result that the shooks are equal in strength and by drawing the shooks together by the tie rods and then by placing the boards of the shooks under a compression force any lateral stresses, such as impacts against the same, are distributed and taken up uniformly throughout the entire shook. Also by the arrangement of the tie rods in uniting the elements of the case the tie rods will be under tension and the wood of the shooks act under compression and the pull of the tie rods will not be against one another but against the resiliency of the wood with the result that there is an equalized or balanced distribution of strength and any stresses communicated to a member of the case is transmitted to and taken up in all of the members of the case. No element of the case, the tie rods or the wood of the shooks is placed under sheer, nor are the shooks placed under undue stress at the terminals or edges thereof, as in securing the shooks in the case there is no penetration and disruptive effect of the marginal portions of the shooks by fastening means, such as nails, screws and the like. The tie rods extend through the shooks at the corners of the case and to prevent

the nuts as they are screwed onto the tie rods exerting a crushing and disruptive effect upon the wood of the shooks, and to also protect the corners metallic cap members 21 are engaged upon the corners of the case to embrace the side and end members and the top or bottom member, the tie rods being extended through openings in said caps and the nuts abutting the same.

To further reinforce and strengthen the case, tie rods are extended longitudinally through tunnels arranged in the side, top and bottom members of the case. These rods are shown as extended longitudinally intermediate the shooks, as at 23. To provide tunnels between the shooks for the passage of said rods a tongue, as shown at 16^a in Figure 3, is removed from the end member of the shook and the board is provided with a groove 15^a similar to the grooves 15 adapted to be opposed to a groove 15 in the edge of the adjacent shook providing a tunnel of greater width in the direction of the width of the boards and permitting the tie rods to be displaced laterally to avoid tie rods extending through the boards or between the shooks of case members in some forms of the case. If desired, tie rods, as the rods 28, may be extended longitudinally through tunnels arranged intermediate the side edges of boards of the shooks, for which purpose a tongue 16^a is removed from one of the intermediate boards and provided with a groove, as indicated at 15^b in Figure 3. The tie rods 28 extending through the ends of the shooks having the tenons mortised therein, as shown in Figure 6, function to draw the top and bottom members adjacent the side edges and intermediate the length thereof to the side members of the case, draw the side members adjacent the side edges and intermediate the length to the ends of the end members of the case and draw the end members adjacent the side edges and intermediate the length thereof to the ends of the top and bottom members, said tie rods are extended through a leg of angle iron members 29, the angle members engaging over the joined portions of shooks and the side marginal portions of the case members, as clearly shown in Figures 5 and 6.

In Figure 7 there is shown a modified arrangement of shipping case or crate constructed from shooks, as shown in Figure 1, and utilizing four of said shooks a, a', a2 and a3 in the side members, four shooks c, c', c2 and c3 in the top and bottom members, and two shooks b, b' in the end members. Angle iron members 30 are engaged over the angle at the juncture of the side members with the end members and angle iron members 31 and 32 engaged over the angle at the juncture of the top member with the end members and side members, respectively, the angle iron members being secured by suitable means, such as screws. In constructing the case the side members are united to the end members by tie rods 22^a extended through the mortise tunnels of the shooks similar to the tie rods 22^b in the Figure 5 arrangement, and through the angle iron members 30 and the shooks as well as the boards of the shooks being drawn together under a compression force by nuts threaded onto the tie rods at the outer side of the angle iron members. The end members are secured to the side members by tie rods 22^b extended through the tunnels in the shooks of the end members and through the angle iron members 30 and nuts threaded onto the ends thereof to draw together under a compression force the shooks and the boards of the shooks of the end members of the case. The top member of the case is united

to the end members by tie rods 22^c extended through the tunnels in the shooks of the top members and the angle iron members 31 and nuts threaded onto the ends thereof at the outer side of the angle iron members, and the bottom member is united to the side members by tie rods 22^d extended through the mortise tunnel and the shooks of the bottom member and through the shooks of the side members a, a', a2, a3 of the case.

To reinforce the case and adapt it to be readily moved, as on rollers, the case is provided with skids 33, one extending longitudinally below the edge of each side member of the case and a part of the bottom case member and one skid extending longitudinally of the bottom member intermediate the ends of the shooks thereof. While the skids may consist of one piece to reduce the cost they are, as shown in Figures 8 and 9, constructed of three members, preferably wood, in sidewise relation, each member being of a thickness less than the width thereof and secured together by bolts 34. In the arrangement of skids shown in Figure 9, plates 35 of greater width than the skid members are interposed between the members of the skids and the longitudinal edges are flanged laterally to extend in opposite directions, as shown in 35' and 35'', whereby one flange of one plate will overlie one outer member of the skid and the flange of the other plate overlie the other outer member of the skid, and the flanges at the opposite edges of the plate overlying the intermediate member of the skids. To connect the skids to the case and further reinforce and strengthen the case tie rods 28' are extended through tunnels, as at 15^a, formed between the adjacent shooks of the side members of the case, the nut or head at one end of the tie rods being countersunk into the skids and the opposite ends of the tie rods extended through the angle iron members 32 and nuts threaded thereon. The intermediate skid is connected to the case by tie rods 28'' extended through the tunnel, as at 15^a, between the shooks of the end members and said skid with the nut or head at one end countersunk into the skid and the opposite end of the tie rods extended through the angle iron members 31 and nuts threaded thereon. A board may be secured to the ends of the skids to close the space at the bottom of the case between the skids to give a finished appearance to the case.

In Figures 11 to 14 there is shown a further modified embodiment of the invention constructed from shooks, as shown in Figure 1. The side, top and bottom members of the case are constructed of four shooks and the end members of two shooks the same as in Figure 7, the side and end members engaging upon the bottom member with the top member engaging upon the ends of the side and end members. Instead of the side and end members being arranged in abutting relation and an angle iron engaged thereover, as in the Figure 7 arrangement, angle iron members 30' through which the side and end members are united are arranged so that the outer face of one leg of said angle iron members engages a side edge of the side members of the case and the other leg engages the side edge of an end member of the case, as clearly shown in Figure 13, and the tie rods 22^a extended through the mortise tunnels of the side members and the tie rods 22^b extended through the mortise tunnels in the end members are extended through openings in said angle iron

members 30'. The angle iron members 31' and 32' are engaged over the angles formed at the juncture of the top members with the end and side members. The tie rods 27^a extending through the mortise tunnels in the shocks in the top member of the case are extended through the angle iron members 31' to unite it to the end members, and the bottom member is connected to the end members by extending the tie rods 22^a in the mortise tunnels of the shocks thereof through the shocks b, b' of the end members of the case. The case is also provided with skids 33' extending longitudinally of the case below the side members and intermediate the bottom member. To connect the skids extending below the side members to and reinforce the case the tie rods 28' extending through the tunnels between the shocks of the side members are extended through said skids with the nut or head at one end countersunk into the skids, as shown in Figures 12 and 14, the opposite ends of the tie rods extending through the angle iron members 32'. The intermediate skid is connected to the case by the tie rods 28" extended through the tunnels between the shocks of the end members of the case and the angle iron members 31'. To make the case pilfer proof angular caps 37 are engaged over the corners formed by the side and end members with the top and bottom members of the case, said caps being secured to the case by bolts 38 extended inwardly through said cap members and the shocks of the case members and nuts threaded onto the bolts within the case. To facilitate securing the nuts onto said bolts from the interior of the case it is provided with an access opening having a hinged closure, as shown at 39, arranged with means to secure the closure in closed position, as by a padlock or the like. This opening to the case may also be utilized for the passage of articles to be enclosed in the case.

In the arrangement of cases shown in Figures 7 and 11 the top and bottom members are also united to the side members by the tie rods 28^a extended through the tunnels between the shocks of said top and bottom members, said tie rods of the top member extending through the angle iron members 32' and of the bottom member through the shocks of the side members, washers being interposed between the nuts and heads of the tie rods to prevent undue compression of the wood of the shocks. In the arrangement of the shocks of the top, bottom and side members as shown in Figures 7 and 11 wherein the tie rods 23', 28^a intersect each other, as shown in Figure 14, by the arrangement of making the tunnels between the shocks of increased width one of said tie rods, for instance the tie rods extending through the tunnels between the shocks of the side members of the case, may be readily disposed at the side of the tie rods extended through the tunnels between the shocks of the top and bottom members of the case. Also to displace the tie rods in the mortise tunnels of the shocks of one member of the case relative to another member of the case and thus facilitate the screwing of the nuts onto the tie rods in the mortise tunnels, the mortise tunnels are of increased width relative to the diameter of

the tie rods. To further strengthen the case, a reinforcing member may be interposed between the top member and the side members of the case, as shown at 40 in Figure 14.

Having described my invention, I claim:

1. In a shook or panel, a plurality of wood pieces of equal length having a pair of spaced tongues on one longitudinal edge and a pair of grooves in the opposite longitudinal edge and a wood piece having a tongue and a groove on one longitudinal edge and a pair of grooves in the opposite longitudinal edge, and all of the wood pieces having a mortise in the opposite ends extending in the direction of the width and transversely of the grain thereof midway the thickness of the wood pieces, and said wood pieces assembled and joined in edgewise relation by the tongues and grooves with the mortises disposed in alinement and the one wood piece with the tongue and groove on the same longitudinal edge disposed intermediate the assembled wood pieces and said groove opposed to a groove in the edge of the adjacent wood piece and forming therewith a passage extending in a direction longitudinally of said wood pieces, and splines of a width less than the depth of and engaged in the mortises to extend transversely of the assembled wood pieces adapted to take up the stresses of forces transmitted laterally of the assembled wood pieces, and said splines spaced from and forming with the bottom portion of the mortises tunnels extending transversely of the assembled pieces adapted for the engagement of means to draw the assembled wood pieces together in edgewise relation.

2. In a shook or panel for cases and the like, a plurality of sections adapted to be disposed in edgewise relation in the shook or panel, each section consisting of a plurality of wood pieces having a mortise in the opposite ends extending in the direction of the width and transversely of the grain of the wood pieces and having a pair of tongues on one edge and a pair of grooves in the opposite edge extending longitudinally and in the direction of the grain of the wood pieces, and a wood piece to constitute the end wood piece of a section having a tongue and a groove extending parallelly of the tongue in the outer edge thereof and said groove adapted to be disposed opposite a groove in the outer edge of the wood piece at the end of the adjacent section and form therewith a passage extending longitudinally of the wood pieces of the sections, and the wood pieces of the sections joined in edgewise relation by the tongues and grooves with the mortises disposed in alinement, splines of a length equal to the width of the shook sections and of a width less than the depth of the mortises in the ends of the wood pieces engaged in the mortises and extending transversely of the sections of the shook and positioned in the mortises in spaced relation to and forming with the bottom portion thereof tunnels extending transversely of the plurality of shook sections, and means extended through said tunnels adapted to connect the sections of the shook in edgewise relation and place and hold the plurality of sections of the shook under an edgewise compression force.

GEORGE G. WHEAT.
